ATTORNEYS

UNITED STATES PATENT OFFICE.

MAXIME P. FERRER, OF BROOKLYN, NEW YORK.

PUMP.

Application filed August 18, 1921. Serial No. 493,370.

To all whom it may concern:

Be it known that I, MAXIME P. FERRER, a citizen of the United States, and a resident of the city of New York, borough of Brooklyn, county of Kings, and State of New York, have invented a new and Improved Pump, of which the following is a description.

My invention relates to a rotary pump 10 and more particularly relates to a pump adapted for pumping viscous substances.

The general object of the invention is to provide a pump for the indicated purpose improved in various particulars whereby 15 the flow of the viscous material will be facilitated and efficiency otherwise promoted.

The invention has also for an important object to provide a steam jacketed pump cylinder for the heating of the viscous material and to utilize the steam as a motive 20 fluid for turning the pump.

A further object of the invention is to provide a pump in which the steam employed for heating and as a motive fluid is caused to mix with the pumped material 25 and to have a siphoning action to assist the pump.

The nature of the invention and its distinctive features and advantages will more 30 clearly appear as the description proceeds.

Reference is to be had to the accompanying drawings forming a part of this specification, it being understood that the drawings are merely illustrative of one example 35 of the invention.

Figure 1 is a vertical section of a pump embodying my invention;

Figure 2 is a horizontal section on the line 2-2, Figure 1;

Figure 3 is a detail in vertical section on an enlarged scale as indicated by the line 3-3, Figure 1.

In carrying out my invention in accordance with the illustrated example, a cylinder 45 body 10 is provided, having an inner wall 11 spaced from the outer shell to provide a steam space 12 resulting in a steam jacketed cylinder. The inner wall 11 is in practice preferably separate from the outer shell 50 and has an annular outwardly directed flange 13 at the bottom secured by bolts 14 which pass through the bottom of the shell 10 and through an annular peripheral flange 55 15 on grid or open-work guard 16 extending across the cylinder at the lower end. A steam pipe 17 leads from any suitable source

of supply (not shown) into the steam space 12.

A vertical shaft 18 is provided centrally in the cylinder and carries blades 19 at the top and blades 20 at the lower end, the hubs of the blades being keyed on reduced threaded ends of the shaft 18 and held by nuts 21. The shaft 18 turns in upper and lower bearings 22 formed by the spiders 23 integral 65 with the inner wall 11.

Rigid with the upper blades 19 is an annular series of turbine blades 24 to which steam is directed through oblique ports 25 leading from the steam space 12 through 70 an annular flange 26 on the wall 11 at the top. The flange 26 is secured in the illustrated example by bolts 27 and nuts 28, the bolts passing through a laterally directed annular flange 29 on the upper end of the 75 outer shell 10 and through an annular lateral flange 30 on a cylindrical extension 31 within which the upper blades 19 and turbine blades 24 revolve. The extension 31 has connected to it in any suitable manner 80 a pipe 32 leading to any desired point of delivery for the pumped material. In practice a drain cock 33 may be provided on the outer shell 10 at the bottom to drain 85 water of condensation from the steam space 12.

With the described construction steam from the pipe 17 will fill the steam jacket and from the latter the steam will escape through the ports 25 and be directed against 90 the blades 24 to turn the same and with them the blades 19, shaft 18, and blades 20. The blades 19 and 20 are at such an angle as to pump the viscous substance through the guard 16 to the extension 31 and pipe 32. 95 The steam, it will be observed, thus functions to heat the pump cylinder and to drive the pump. The steam is caused furthermore to mix with the pumped material in the extension 31 and pipe 32 to have a 100 siphoning action to assist the pump.

In use the pump is set bodily into a tank of the viscous material to be pumped so that the heat may be utilized to the fullest extent not only in heating the material as 105 it passes through the pump but also to heat the material in the tank.

I would state in conclusion that while the illustrated example constitutes a practical embodiment of my invention, I do not limit 110 myself strictly to the exact details herein illustrated, since, manifestly, the same can

be considerably varied without departure from the spirit of the invention as defined in the appended claims.

Having thus described my invention, I claim:

1. A steam pump of the class described comprising a jacketed pump cylinder bodily submergible with its jacket in the material to be pumped, steam supply means for the steam jacket of the cylinder, and drive means in position to be submerged with the submergence of the cylinder and actuated by the steam escaping from the steam jacket. 40
2. A pump of the class described including a cylinder, pumping means associated with the cylinder, a fluid-driven means rigid with the pumping means to actuate the same, steam-heating means associated with the cylinder, and means in advance of said fluid-driven means to direct the steam from the heating means to said second-mentioned means after the steam leaves the heating means. 45
3. A pump of the class described including a rigid cylinder, a rotary pumping means within the cylinder, a turbine rigid with said pumping means beyond the cylinder, and means to direct a motive fluid to said turbine. 50
4. A pump of the class described including a cylinder, pumping means associated with the cylinder, means constituting an extension of the cylinder to which the pumping means delivers, a turbine rigid with the pumping means and disposed within the second-mentioned means, and means to direct a motive fluid against said turbine. 55
5. A pump of the class described including a steam-jacketed cylinder, rotary pumping means associated therewith, an extension on the cylinder to which the pump discharges, a turbine rigid with the pumping means and disposed within said extension, and means to direct the steam from the steam jacket against said turbine. 60
6. A pump of the class described including a cylinder having an outer shell and a separate inner wall spaced therefrom to form a steam jacket, said wall formed with annular flanges at the top and bottom, means securing the lower flange to the bottom of the outer shell, an extension about said shell, means securing said extension to the shell and to the upper flange of the inner wall, a rotary pump means associated with the cylinder, bearings rigid with said inner wall in which the pumping means turn, and a turbine rigid with the pumping means and disposed above the upper flange of the inner wall, said flange having a port for the passage of steam from the steam jacket to the turbine, and means to supply steam to the steam jacket. 65
7. A pump of the class described including an outer shell, an inner wall spaced from the shell to provide a jacket and formed with an upper flange, bearings rigid with the inner wall, rotary pumping means turning with said bearings, and a turbine rigid with the pumping means and disposed on the said flange, said flange having a port to direct steam from the steam jacket to said turbine. 70

MAXIME P. FERRER.
